KNITTING MACHINE

Frank G. Weisbecker, Glenside, Pa., assignor to
Hosiery Patents Incorporated, Lansdale, Pa., a
corporation of Pennsylvania

Application November 5, 1937, Serial No. 173,611

18 Claims. (Cl. 66—126)

The present invention relates to improvements in knitting machinery, and more particularly to improvements in the yarn carriers which lay yarn along the sinkers and needles of straight knitting machines.

5 A yarn carrier of the type to which the present invention relates, is disclosed in my prior Patent No. 2,014,341, dated September 10, 1935. That patent explains the usual operation of yarn carriers in a straight knitting machine. My prior patent also discusses certain problems which arise during yarn laying movement of yarn carriers, and which are solved by both the invention of that patent and the invention disclosed herein.

10 The present invention is in a yielding or flexible guide associated with a yarn carrier for laying the yarn thereof along the sinkers and needles of a straight knitting machine.

15 It is one of the objects of this invention to provide a yielding, yarn carrier guide which requires no inner lining for the protection of the yarn passing through the guide.

Another object is to provide a yielding, yarn carrier guide which is not likely to catch or cut 20 the yarn passing therethrough in a yarn laying movement.

25 A further object is to provide a yielding, yarn carrier guide which is relatively simple and inexpensive to manufacture.

30 Another object is to provide a yielding, yarn carrier guide which has pronounced wear-resisting properties.

35 A still further object is to provide a yarn carrier guide with a flexible characteristic which may be easily controlled and determined in the manufacture of the guide.

Another object is to provide a flexible, yarn carrier guide with its flexibility limited to only a portion of the length of the guide.

40 A further object is to provide a one-piece, yielding, yarn carrier guide to serve as the sole means for guiding the yarn at the yarn laying end of the yarn carrier.

45 Other objects will appear from the following description, the appended claims, and the accompanying drawing.

In the drawing, Fig. 1 is a perspective view of a yarn carrier provided with a yielding yarn guide embodying the present invention.

50 Figs. 2 and 3, respectively, are side elevational and end views, on enlarged scale, of the yielding yarn guide shown in Fig. 1.

Figs. 4 and 5, respectively, are side elevational and end views of a different form of yielding yarn 55 guide embodying the present invention.

Figs. 6 and 7, respectively, are side elevational and end views of a further form of yielding yarn guide embodying the present invention.

Figs. 8 and 9, respectively, are side elevational and longitudinal cross-sectional views of another form of this invention.

Fig. 10 shows a modified form for the tip of yarn carrier guide.

Referring now to the drawing, Fig. 1 shows a complete yarn carrier comprising a supporting arm 11 and a yielding yarn guide 12 embodying the present invention. The supporting arm 1, according to usual practice, may be of rigid construction. The yielding yarn guide 12 may be of any material suited to the purposes of this invention, although steel or some other metal is preferred. A plurality of these guides 12 may be formed by cutting tubular stock into cylinders of the desired length, and providing each cylinder with two or more helical slots 13 in its walls to 20 secure the desired flexibility. The slots 13 may be formed by a cutting operation, and their number, extent and pitch are chosen to secure the desired flexibility in the completed yarn guide.

If desired, a flexible yarn guide according to 25 this invention may be secured by cutting a single, continuous helical slot 14 through the walls of a guide tube 15, as shown in Fig. 4.

Another form of guide tube embodying this invention may be secured by cutting one or more 30 slots 16 along planes normal to the longitudinal axis of a tube 17 as shown in Figs. 6 and 7.

Another form of this invention is shown in Figs. 8 and 9. According to these figures, the guide tube is formed by a helical coil 21 of metallic ribbon or flat wire, the convolutions of which are in spaced relation. One end 20 of the Figs. 35 8 and 9 guide may be tapered if desired, as shown in the drawing. The spaces between the convolutions in the areas 18 and 20 are filled with 40 suitable material 24. This material is preferably metal and may be incorporated into the tube walls in a welding operation. Consequently, the guide tube of Figs. 8 and 9 will have continuous, 45 integral, imperforate walls in the areas 18 and 20, and a single, relatively short, helical slot 22 for the area 18.

The extent of the slotted area along the guide tubes is indicated at 19 in the figures. The slotted area may have such extent as will secure the desired results. Generally the slotted area 19 will not extend over one-half the length of the guide tube. According to the preferred practice of this invention, the extent of the slotted area 18 55

is not over one-third of the tube length, as shown in Figs. 2, 4, 6 and 8.

Only a limited extent for the slotted area 19 is required in actual practice of this invention to 5 provide the desired flexibility. A limited extent for the slotted area 19 offers the advantage that while the guide tube has sufficient flexibility to prevent damage in the event of the guide tube striking a sinker or other part of the knitting 10 machine, it still has enough rigidity under normal operating conditions to lay the yarn properly and avoid imperfect knitting.

Each guide tube is preferably slotted so that the intervening strips or bands, for example, see 15 strips 26 in Fig. 2, have a non-circular cross-sectional shape. This non-circular shape is found to increase the rigidity of the guide tube, while still providing sufficient flexibility in event of collision between the guide tube and a part of the 20 knitting machine.

The interior surfaces or bores of the four forms of guide tubes shown in the drawing are 25 preferably smooth so as not to interfere with the feeding movement of yarn passing through the guide tubes. Should it be necessary, the 30 guide tubes may have their interior wall surfaces ground or smoothed by a machining operation.

As a further step in the manufacture of the 35 guide tubes, they may have their lower end portions 20 hardened to improve their wear resisting characteristics. Experience shows that the tube ends 20 are subject to greater wear by the 40 yarn in yarn laying operations than are the guide tube portions 18 and 19. The hardening operation may be carried out by means of a conventional process involving heat treatment and chilling. The tube portion 19 should be protected during 45 the hardening of portion 20, so that it (portion 19) does not lose its flexible characteristic.

While only the guide tube of Figs. 8 and 9 is 50 shown with a tapered end portion 20, it will be understood that the corresponding portion of the other guide tubes may be provided with the same 55 shape. If desired, the end portion 20 of the guide tubes may be somewhat flattened to provide an oval shaped end as shown at 23 in Fig. 10.

The portion 18 of the guide tubes is preferably 60 somewhat longer than guide tube portion 20. This portion 18 constitutes the inlet end of its 65 guide tube and is rigidly secured to supporting arm 11, as shown in Fig. 1, by welding, soldering, or in any desired manner. The guide tube portion 20 may be relatively short and constitutes 70 the outlet end of its guide tube.

The ends of the slots in the guide tubes may be 75 rounded, as shown for example at 25 in Figs. 2, 4 and 6, so as to further avoid sharp corners, in which yarn passing through the tube might be caught.

The terms "tube" and "bore" are used generically in the foregoing description and the appended claims to cover cylindrical and other shapes which are suited to the purposes of this 85 invention and which will accomplish the desired end.

It will be understood that the foregoing description is only illustrative, and that the invention includes all embodiments coming within the 90 scope of the appended claims.

What I claim is:

1. For use in a yarn carrier of straight knitting machines, a tube to cooperate with said carrier and form a yielding means for laying the 95 yarn of said carrier along the sinkers and needles

of the knitting machine, said tube intermediate its ends having one or more slots extending through its walls, at least one end of said tube being without slots and having a smooth bore.

2. For use in a yarn carrier of straight knitting 5 machines, a tube to cooperate with said carrier and form a yielding means for laying the yarn of said carrier along the sinkers and needles of the knitting machine, the ends of said tube having imperforate walls and a smooth bore, said tube 10 intermediate said ends having one or more slots extending through its walls.

3. For use in a yarn carrier of straight knitting 15 machines, a tube to cooperate with said carrier and form a yielding means for laying the 20 yarn of said carrier along the sinkers and needles of the knitting machine, each of the ends of said tube having walls of integral formation in both a circumferential and longitudinal direction, each tube end also presenting an opening free of irregularities, said tube intermediate said ends having one or more slots extending through its walls.

4. For use in a yarn carrier of straight knitting 25 machines, a tube to cooperate with said carrier and form a yielding means for laying the 30 yarn of said carrier along the sinkers and needles of the knitting machine, said tube having a continuous helical slot extending through its walls and terminating short of at least one of its ends. 35

5. For use in a yarn carrier of straight knitting 40 machines, a tube to cooperate with said carrier and form a yielding means for laying the 45 yarn of said carrier along the sinkers and needles of the knitting machine, said tube comprising a cylinder having end and intermediate portions, said cylinder also having one or more slots 50 extending through its walls and confined to said intermediate portion.

6. For use in a yarn carrier of straight knitting 55 machines, a tube to cooperate with said carrier and form a yielding means for laying the 60 yarn of said carrier along the sinkers and needles of the knitting machine, said tube having a series of disconnected slots extending through its 65 walls.

7. For use in a yarn carrier of straight knitting 70 machines, a tube to cooperate with said carrier and form a yielding means for laying the 75 yarn of said carrier along the sinkers and needles of the knitting machine, said tube having at least one slot extending through its walls and cut on a plane normal to the longitudinal axis of the tube.

8. For use in a yarn carrier of straight knitting 80 machines, a tube to cooperate with said carrier and form a yielding means for laying the 85 yarn of said carrier along the sinkers and needles of the knitting machine, said tube having a plurality of disconnected helical slots extending through its walls and spaced longitudinally of 90 the tube.

9. For use in a yarn carrier of straight knitting 95 machines, a tube to cooperate with said carrier and form a yielding means for laying the 100 yarn of said carrier along the sinkers and needles of the knitting machine, said tube comprising a helical coil spring having its convolutions in spaced relation, the spaces between adjacent convolutions at both ends of the tube being filled with metallic material, and the spaces between 105 convolutions intermediate said tube ends being free of material.

10. For use in a yarn carrier of straight knitting 110 machines, a tube to cooperate with said carrier and form a yielding means for laying the 115

yarn of said carrier along the sinkers and needles of the knitting machine, the ends of said tube having imperforate walls and a smooth bore, said tube intermediate said ends having its walls slotted to provide one or more strips connecting said ends, said strips having a non-circular cross-sectional shape.

11. For use in a yarn carrier of straight knitting machines, a guide tube to cooperate with said carrier and form a yielding means for laying the yarn of said carrier along the sinkers and needles of a knitting machine, at least a portion of said tube intermediate its ends being relatively resilient for yielding movement to permit the tip 10 end of the guide tube to ride over an obstructing sinker during yarn laying operations, said guide tube being adapted to be held in the carrier with said resilient portion free to flex for said yielding movement, and the outlet end or tip of said 15 tube being of relatively inflexible construction and more wear-resistant than said flexible portion, said tube being free of internal shoulders and projections.

12. For use in a yarn carrier of straight knitting machines, a substantially cylindrical tube to cooperate with said carrier and form a yielding means for laying the yarn of said carrier along the sinkers and needles of the knitting machine; said tube having end portions with imperforate 20 walls and smooth interior surfaces, having at least one of said end portions of relatively rigid construction to serve as a yarn laying tip, having an intermediate portion of relatively resilient construction to permit lateral yielding movement 25 of said yarn laying tip relative to the other end of said tube, and being free of internal shoulders and projections.

13. For use in a yarn carrier of straight knitting machines, a substantially cylindrical tube to cooperate with said carrier and form a yielding means for laying the yarn of said carrier along the sinkers and needles of the knitting machine; said tube having end portions with imperforate 30 walls and smooth interior surfaces, having at least one of said end portions of relatively rigid construction to serve as a yarn laying tip, having an intermediate portion comprising resilient convolutions to permit lateral yielding movement 35 of said yarn laying tip relative to the other end of said tube, and being free of internal shoulders and projections.

14. In a yarn carrier for straight knitting machines, the combination of a supporting arm, and a substantially cylindrical tube supported 40 by said arm for laying the yarn thereof along the sinkers and needles of the knitting machine; said tube having end portions with imperforate 45 walls and smooth interior surfaces, having at least one of said end portions of relatively rigid construction to serve as a yarn laying tip, being free throughout its length of internal shoulders and projections, being relatively resilient intermediate its ends, and being so supported by said 50

arm that said resilient portion may flex and the yarn laying tip may be deflected in event of the tube engaging an obstruction during yarn laying operations.

15. In a yarn carrier for straight knitting machines, the combination of a supporting arm, and a substantially cylindrical tube supported by 5 said arm for laying the yarn thereof along the sinkers and needles of the knitting machine; said tube having end portions with imperforate 10 walls and smooth interior surfaces, having at least one of said end portions of relatively rigid construction to serve as a yarn laying tip, being free throughout its length of internal shoulders and projections, having an intermediate portion 15 thereof comprising resilient convolutions, and being so supported by said arm that said resilient portion may flex and the yarn laying tip may be deflected in event of the tube engaging an obstruction during yarn laying operations. 20

16. For use in a yarn carrier of straight knitting machines, a guide for cooperating with said carrier and forming a yielding means for laying the yarn of said carrier along the sinkers and needles of the knitting machine, said guide comprising a tube having adjacent portions at at least one end thereof bonded together by fusion joint, and having the tip of said tube end of integral solid wall formation, said tube having at least its intermediate part of flexible construction 30 and being free of internal shoulders and projections. 25

17. For use in a yarn carrier of straight knitting machines, a guide for cooperating with said carrier and forming a yielding means for laying the yarn of said carrier along the sinkers and needles of the knitting machine, said guide comprising a tube formed of coiled wire, the adjacent convolutions of said wire at one end of said tube being bonded together by a fusion joint to 40 provide a yarn laying tip of integral solid wall formation, said tube having at least an intermediate part thereof free to yield in event of said tip engaging an obstruction during use of the tube in a knitting operation, said tube also 45 being free of internal shoulders and projections. 35

18. For use in a yarn carrier of straight knitting machines; a substantially tubular yarn guide to cooperate with said carrier and form a yielding means for laying the yarn of said carrier along 50 the sinkers and needles of a knitting machine; said tubular yarn guide having at least an intermediate portion thereof formed of relatively resilient construction, having a gradually tapered section intermediate its ends whereby one guide 55 end has a smaller outer diameter than the other guide end, having its larger end of substantially cylindrical shape, having imperforate walls and smooth interior surfaces for its opposite ends, and being free throughout its length of internal 60 shoulders and projections. 60

FRANK G. WEISBECKER.
